UNITED STATES PATENT OFFICE.

JOHN J. HALLIHAN, OF CHARTLEY, MASSACHUSETTS, ASSIGNOR TO FREEMAN-
DAUGHADAY CO., OF CHARTLEY, MASSACHUSETTS, A CORPORATION OF MASSA-
CHUSETTS, ALSO DOING BUSINESS AS PROVIDENCE COLLAR BUTTON COMPANY,
OF PROVIDENCE, RHODE ISLAND.

SEPARABLE CUFF BUTTON.

Application filed October 28, 1925. Serial No. 65,475.

This invention relates to an improved construction of separable cuff button, and has for its object to provide a cuff button of this character which comprises cooperating stud and socket members, each formed of a single piece of sheet stock, the socket member carrying a spring ring in its inner head into which the stud portion of the stud member is snapped to releasably hold the button members together.

With these and other objects in view, the invention consists of certain novel features of construction, as will be more fully described, and particularly pointed out in the appended claims.

In the accompanying drawings, the figures herein illustrated are greatly enlarged over their actual size.

Figure 1 is a sectional side elevation showing the two members of the cuff button connected.

Figure 2 is a side elevation of the socket member being partially broken away and showing the members separated.

Figure 3 shows one of the blanks of the stud member.

Figure 4 shows the blank a little further developed with the stud portion provided with a recessed neck.

Figure 5 is the first blank of the socket member.

Figure 6 shows the same as having a reduced shank portion.

Figure 7 is a section on line 7—7 of Figure 1, showing the split ring as held in the socket member to engage the neck portion of the stud member.

Figure 8 is a view of the split ring detached.

It is found in the practical construction of cuff buttons of this character, of advantage to form each of the members of the button with inner and outer heads and to form each of these members from a single piece of sheet stock; also to provide an annular recess in the neck portion of the stud and a split ring in the annular recess in the inner head of the socket member. This annular recess is formed in the inner wall of the head is of the maximum size to receive a

50 relatively large ring which is provided with the maximum flexibility and is adapted to

exert the maximum holding or gripping action on the stud of the opposite member, the diameter of the stud member being nearly 55 that of its inner head flange and is shaped to snap into and be gripped by said enlarged ring; and the following is a detailed description of the present embodiment of my invention and showing one construction of 60 cuff button members by which these advantageous results may be accomplished.

With reference to the drawings, 10 designates the stud member of my improved separable cuff button, the same having a shank 65 portion 11 with an enlarged flange 12 formed at the outer head portion thereof, and this flange is herein shown as having its edge 13 turned over that of the outer head-plate 14 which in this case is represented as a plate of pearl. This stud member is provided with an enlarged inner head portion 15 having extending therefrom a projection or stud portion 16, which stud portion 15 is provided with an annularly 75 grooved neck portion 17; the stud portion being of a diameter nearly that of the inner head portion 15.

This stud member is preferably drawn from sheet stock first into the form illustrated in Figure 3, then into the form illustrated in Figure 4, and finally into finished form, as illustrated in Figure 1. The socket member 18 is also formed from sheet stock first into the short flange tube 85 shown in Figure 5, then into the shape shown in Figure 6, with its shank portion reduced and finally into the shape illustrated in Figure 1.

The outer end 19 of this socket member 90 is flanged and its edge 20 is herein shown as being rolled over that of the finished head plate 21 which in this particular case is shown as being a plate of pearl but any suitable finished head may be employed in 95 either of the button members with the edge of one rolled over that of the other to connect the two parts together.

The inner head portion 22 of this socket member is recessed on its inner surface as 100 at 23, forming a beaded edge and the inner surface of the bead forming an annular recess in which a split ring 24 is set and the edge 25 of this head is rolled or turned in-

wardly over this ring to retain it loosely in operative position therein.

By this construction, it will be observed that the split or gripping ring is of a size

- 5 nearly that of the inner head of the member to which it is attached and the gripping surface serves as an effective retaining means when engaging the corresponding groove 17 in the neck of the stud member.
- 10 Thus by this construction, I have provided a button having stud and socket members, the stud portion of which is of the maximum size and to be engaged by a split ring of a correspondingly larger size to receive
- 15 it, and the engaging surface of this ring and stud portions serve to firmly hold the two button members against accidental separation and also permit the employment of a spring ring which has the maximum amount
- 20 of flexibility.

My improved separable button is extremely simple, practical and inexpensive in construction owing to the fact that each of the members is formed from a single piece of

25 sheet stock drawn and swaged into the desired shape and the extended surfaces of the gripping ring and of the receiving groove of the neck portion cooperate to provide button members having great holding power

30 and being adapted to be snapped together and disconnected with just the proper amount of resistance.

The foregoing description is directed solely towards the construction illustrated,

35 but I desire it to be understood that I reserve the privilege of resorting to all the mechanical changes to which the device is susceptible, the invention being defined and

limited only by the terms of the appended claims.

40

I claim:

1. A separable cuff button comprising stud and socket members, each having inner and outer heads and each formed of a single piece of sheet stock, said stud member having a stud portion projecting from its inner head with an annularly-grooved neck portion, said socket member having a stud-receiving opening in its inner head, the inner wall of said head being provided with an annular recess, a spring ring loosely mounted in said recess and the stock at the edge of said opening being turned over said ring to hold it in place, said ring serving to engage said neck portion to releasably hold said button members together.

2. A separable cuff button comprising stud and socket members, each having similar sized inner and outer heads, and each formed of a single piece of sheet stock, said socket member having a stud-receiving opening in its inner head of a diameter slightly less than that of the diameter of said outer head, the stock of said inner head adjacent its outer periphery being beaded or rolled inwardly to provide an inner annular recess, a spring ring of a diameter to loosely fit in said recess, said stud member having a stud portion projecting from its inner head of a diameter slightly less than that of its inner head and shaped to snap into said ring to releasably hold said button members together.

In testimony whereof I affix my signature.

JOHN J. HALLIHAN.
